UNITED STATES PATENT OFFICE.

JAMES W. KENYON, OF MUSKEGON, MICHIGAN, ASSIGNOR TO THE SHAW-WALKER COMPANY, OF MUSKEGON, MICHIGAN, A CORPORATION OF MICHIGAN.

SHEET-METAL-CONSTRUCTED CABINET.

1,181,225.

Specification of Letters Patent.

Patented May 2, 1916.

Application filed February 16, 1914. Serial No. 812,930.

To all whom it may concern:

Be it known that I, JAMES W. KENYON, a citizen of the United States, residing at Muskegon, in the county of Muskegon and State of Michigan, have invented new and useful Improvements in Sheet-Metal-Constructed Cabinets, of which the following is a specification.

My present invention relates to sheet metal-constructed cabinets, and its object is to provide a structure of that character which shall be easily and economically manufactured, and which shall be strong and durable under service conditions, as well as pleasing in appearance. This object is attained by, and the invention finds a preferable embodiment in, the structure herein-after described and illustrated by the accompanying drawings, in which:—

Figure 1 is a perspective view of such a structure; Fig. 2 is a similar but fragmentary view of the upper front part thereof; Fig. 3 is a like view of the upper rear part of the same; Fig. 4 is a view similar to Fig. 2, but with the top removed; Fig. 5 is a view similar to Fig. 3, but with the top removed; and Figs. 6, 7, 8, 9 and 10 illustrate modifications; Fig. 6 is a view in perspective of one such modification; Fig. 7 is a similar view of another; Fig. 8 a like view of another; Fig. 9 is a similar view of another modification; and Fig. 10 is still another like view of a fifth modification.

The cabinet is made of metal (as steel) sheets constituting the walls, one being formed with an angularly-disposed flange shaped to provide a ledge or shoulder projecting from the surface of a second wall to which such flange is joined, and to abut against a third wall's like flange similarly projecting from said second wall's said surface.

To illustrate my present invention, three adjoining walls of a cabinet are to be shown,—a top or bottom, a front or back, and one side: in the drawings, the reference character 1 designates the entire cabinet, 2 the top, 3 the bottom, 5 the back, 6 the front (such front in the construction shown being represented by front stiles only), and 8 the sides, 9 designating the body portion of the back or front as distinguished from their flanges 7, and 4 designating such flanges of

the top or bottom as distinguished from their body portions 2 or 3. 55

The top and bottom may be, as shown, of identical and usual form and construction, each being a metal sheet bent and fashioned in well-known manner into the shape of a box lid or cover of ordinary form having a vertically-extending rim at its periphery forming said flange 4, as shown. The flanges 4 and 7 of the walls are integral therewith in all the views excepting Figs. 7 and 9, wherein they are shown of a separate piece 11, in the form of angle bars; these flanges are united to the surface of an adjoining wall, as by welding, and their end portions are shaped to provide the ledges or shoulders 10 adapted to abut against a third wall's like flange similarly united to said surface. It will be seen that the two flanges aforesaid, thus abutting and projecting from said surface, present a paneled appearance of that wall to whose surface they are thus joined.

In Figs. 8 and 9, the end portions of the abutting flanges are "mitered", while in the other views, the end portion of one flange abuts against the side of the other; and the shape of the parts may of course be varied without departing from my invention.

In Fig. 6, the side is composed of two metal sheets laid together side by side, and the front stile 6 is bent to overlie their edges 85 and the outer side of the outer sheet: in Fig. 7 the member 9 abuts against the edge of the member 8, and the corner piece 11 overlies the outer side of both such members: in Fig. 8, 9 is bent at right angles 90 forming a flange 7 which overlies the member 8: in Fig. 9 the member 11, (the corner piece) overlies the members 8 and 9: and in Fig. 10, the stile 6 is bent to overlie both the inner and the outer sides of the member 8. 95

Not confining myself to details of form and construction shown or described, I claim:—

1. A cabinet having a wall, a second wall 100 with an angularly-disposed flange joined to the first wall and forming a ledge projecting from the first wall's surface, and a third wall having an angularly-disposed flange joined to the first wall and abutting against 105 said ledge, the body portion of the second

wall extending toward the third wall further than the ledge-forming flange of said second wall.

2. A cabinet having a wall, a stile having a central portion and two parallel flanges, one of which flanges is joined to the wall and forms a ledge projecting from the wall's surface, and another wall having an angularly-disposed flange joined to the first wall and abutting against said ledge, the

central portion of the stile extending toward the second wall further than the ledge-forming flange of the stile.

In testimony whereof I have hereunto set my hand in presence of two subscribing witnesses.

JAMES W. KENYON.
